UNITED STATES PATENT OFFICE

162,834

RECEPTACLE FOR ATTACHMENT TO VEHICLE SUN VISORS

Anton C. Janeshutz, Caracas, Venezuela

Application February 27, 1950, Serial No. 8,178

Term of patent 7 years

(Cl. D14—6)

To all whom it may concern:

Be it known that I, Anton C. Janeshutz, a citizen of the United States, residing at Caracas, Venezuela, have invented a new, original, and ornamental Design for Receptacle for Attachment to Vehicle Sun Visors, of which the following is a specification, reference being had to the accompanying drawing, forming a part thereof.

Figure 1 is a front perspective view of a receptacle for attachment to sun visors showing my design; and

Figure 2 is an end elevation looking from the distant end of Figure 1.

The characteristic features of my design reside in the parts shown by means of full lines in the drawing.

I claim:

The ornamental design for a receptacle for attachment to vehicle sun visors, as shown and described.

ANTON C. JANESHUTZ.
